UNITED STATES PATENT OFFICE.

JOHN HENDERSON, OF CADILLAC, MICHIGAN.

STOVE.

1,189,691.

Specification of Letters Patent.

Patented July 4, 1916.

Application filed September 30, 1915. Serial No. 53,292.

To all whom it may concern:

Be it known that I, JOHN HENDERSON, a citizen of the United States, residing at Cadillac, in the county of Wexford and 5 State of Michigan, have invented a new and useful Stove, of which the following is a specification.

The present invention appertains to stoves, and aims to provide a novel and im- 10 proved stove adapted especially for use in chicken brooders, chicken coops, and the like, although the stove may be employed for divers purposes for which it is suitable.

One of the objects of the invention is the 15 provision of a stove which can be suspended within the brooder, coop, or the like, whereby the chickens can rove under the stove, the stove being rotatable whereby it can be properly attended to without the necessity 20 of the attendant or operator walking completely around the stove, and the means which suspends the stove serving to carry off the products of combustion.

Another object of the invention is the 25 provision of a stove of unique construction, the same having an annular fire box or combustion chamber, and having a unique assemblage of the component parts, whereby the heating capacity and efficiency of the stove 30 are enhanced.

The invention also includes a hood above the stove and assembled with the suspension means, whereby the hood can be raised and lowered relative to the stove as desired.

35 With the foregoing and other objects in view which will appear as the description proceeds, the invention resides in the combination and arrangement of parts and in the details of construction hereinafter described 40 and claimed, it being understood that changes in the precise embodiment of the invention herein disclosed can be made within the scope of what is claimed without departing from the spirit of the invention.

45 The invention is illustrated in the accompanying drawings, wherein:—

Figure 1 is a view of the improved structure, one half being shown in elevation, and the other half being shown in vertical section. Fig. 2 is an enlarged horizontal section taken on the line 2—2 of Fig. 1, one half of the stove being illustrated in plan and the other half being illustrated in section, portions being broken away. Fig. 3 is a sec- 50 tional detail taken on the line 3—3 of Fig. 2.

The stove embodies a cylindrical casing

or shell 1 constructed of sheet metal or other suitable material, and having a dome-shaped top 2, the upper end of the casing or jacket 1 having an inturned flange 3 riveted or otherwise secured to the top 2 adjacent the margin of the top. The top is also of sheet metal or other suitable material, and is provided with a central outlet opening 4 for the products of combustion. This opening 4 60 communicates with the lower end of a vertical suspension pipe or flue 5, and the casing 1 is rotatably carried by the lower end of the pendant flue 5. To this end, a ring or annular casting 6 is riveted or otherwise secured upon the top 2 of the casing around the opening 4, and has an annular upstanding flange 7 providing a recess accommodating a collar 8 which is threaded or otherwise secured upon the lower end portion of 65 the flue 5. An annular plate 9 is secured in any suitable manner upon the flange 7, and an annular series of anti-frictional balls 10 are disposed between the collar or flange 8 and the plate 9, said collar and plate being 70 provided with suitable annular ball races for accommodating the balls. The plate 9 which is attached through the medium of the ring 6 to the stove casing, may therefore run upon the balls 10 to allow the casing to be rotated freely. The flue 5 not only acts as a 75 suspension means for the stove, but also serves to carry off the products of combustion from within the stove casing.

Disposed within the vertical casing 1 is 80 a vertical cylindrical drum 11 of smaller diameter than the casing 1 to provide an annular space between said casing and drum, and the drum 11 has a convexed or dome-shaped top or upper end 12. The upper 85 end of the drum 11 is provided with a flange 13 riveted or otherwise secured to the top or head 12, and the top 12 of the drum 11 is disposed adjacent but spaced from the convexed or dome-shaped top 2 of the cas- 90 ing.

A plurality of short pipes or flues 15 are engaged through the tops 2 and 12 of the casing and drum respectively, around the ring 6, and nuts 16 are threaded upon the 95 ends of the flues 15 and bear against the upper and lower surfaces of the tops 2 and 12, whereby the flues 15 not only provide outlets for the upper ends of the drum 11, but also serve the office of stays for connecting the tops of the casing and drum, 100 whereby the drum is held in place within 105 110

the casing. The drum, as well as the casing, is constructed of sheet metal.

Disposed between the casing 1 and the drum 11, that is, between the side walls thereof, is an annular series of radial stays 17 having downturned ears 18 at their ends bearing against the side walls of the casing and drum, and radial bolts 19 are engaged through the ears 18 and the side walls of 10 the casing 1 and drum 11 to secure the stays 17 in place, and to also secure the casing 1 and drum 11 to the ends of said stays. The stays 17 assisted by the flues 15 serve to hold the drum 11 concentric with the casing 1. 15 The stays 17 are disposed between the upper and lower ends of the casing and drum. The stays 17 also serve to support an annular grate 20 which is seated thereon, this grate 20 having suitable slots or openings 20 21 for the upward passage of air therethrough, and for the downward passage of ashes into the annular ash pit below the grate. The annular fire box or combustion chamber is located above the grate between 25 the casing 1 and drum 11, and the flue 5 serves as an outlet for the products of combustion. The grate 20 is preferably composed of upper and lower annular sheet metal plates 22 having an annular sheet of 30 asbestos or fire proof material 23 therebetween, registering slots or openings being provided in the plates 22 and sheet 23.

The top 2 of the casing is provided with a number of fuel openings 24 above the annular fire box at various points around the center of the stove, and the openings 24 are normally closed by covers 25 seating upon the top 2 over said openings, the cover 25 being preferably hinged, as at 26, to the 40 top 2.

The casing 1 and drum 11 have a common bottom, which embodies a pair of semi-circular sections 27 having their side edges hinged together and to the lower ends of 45 the casing and drum, as at 28, and the free portions of the sections 27 are normally held in place against the lower end of the casing 1 by means of pivoted catches 29 carried by diametrically opposite sides of the casing 50 1 adjacent the lower end thereof. The catches 29 are engageable under the free portions of the sections 27. When one catch 29 is released, the corresponding section 27 of the bottom can be swung downwardly for 55 taking out the ashes, or the like, and when both catches 29 are released, the bottoms of the casing and drum are completely opened. Each section 27 of the bottom is provided with an arcuate or semi-circular upstanding 60 flange 30 adjacent its margin, and with a second arcuate or semi-circular flange 31 between the flange 30 and the center of the bottom, and the flanges 30 and 31 of the two bottom sections coöperate to overlap the 65 lower ends of the casing 1 and drum 11,

respectively, upon the outer sides thereof. This provides a tight joint between the bottom and casing and drum.

The air is supplied within the annular ash pit below the grate 20 by means of an annular series of inwardly projecting nozzles 32 having their outer ends attached to the casing 1 between the grate and bottom, the side walls of the casing 1 having openings 33 registering with the nozzles 32 to admit 70 air. The outer ends of the nozzles 32 have outturned annular flanges 34, and rings 35 are slipped upon the nozzles 32 and bear against the flanges 34, said rings 35 being fastened by means of bolts or other securing 80 elements 36 to the casing 1 whereby the nozzles are clamped in place. The passage of air through the openings 33 and nozzles 32 is controlled by an annular damper 37 constructed of sheet metal or other suitable 85 material, the same as the casing and drum and their bottom. A number of outstanding or radial bolts 38 are secured rigidly to the casing 1 between the openings 33 and their outer or free ends are engaged through 90 elongated horizontal slots 39 with which the annular damper 37 is provided, whereby the damper is guided for rotary or oscillatory movement around the stove casing. The damper 37 is provided with inwardly 95 offset portions 41 coöperable with those portions of the casing 1 having the openings 33, whereby when the damper 37 is rotated or oscillated, the portions 41 can be moved over and away from the openings 33 to 100 control the flow of air therethrough as will be evident. The bolts 38 can be loosened or tightened to allow the damper to move easier or harder, whichever is preferred, and the damper 37 is provided at suitable points with handles or knobs 40 whereby the 105 damper can be actuated from various sides of the stove casing.

The means for hanging or suspending the flue or pipe 5 embodies an upper ring or collar 42 surrounding the flue 5 at some distance above the stove, and wedge blocks 43 are driven between the ring 42 and flue 5 for holding the said flue in place relative to said ring, whereby the flue is not liable to slip downwardly under the weight of the stove. The ring or collar 42 has a lower rounded or concaved portion 44 seating in an opening 45 provided in the horizontal supporting plate 46, whereby the flue 5 can swing 110 relative to the supporting plate 46, so that the flue 5 will come to a true vertical position, the stove acting as a plumb bob. This plate 46 may be attached to the ceiling, frame or other support, by means of hangers 115 47 having turn buckles 48 for adjusting them, any suitable number of hangers 47 being employed. The hangers 47 have hooks for engaging in apertures of the plate 46, and the upper ends of the hangers 47 hav- 120 125 130 135 140 145 150 155 160 165 170 175 180

ing eyes or other suitable means for attaching them to the support.

A dome-shaped hood 49 of greater diameter than the stove casing, is slideable vertically upon the flue 5, the exterior surface of the hood 49 being preferably covered with asbestos or equivalent material 50. Secured upon the crest or central portion of the hood 49 is an annular plate or ring 51 which is slideable upon the flue 5, said flue serving as a guide for guiding the hood 49 for vertical movement above the stove.

In order to enable the hood 49 to be raised and lowered, the plate or ring 51 has upward standing eyes or elements 52 engaged by the loops 53 of cables or flexible elements 54, said loops 53 being made secure by clamps 55. The cables 54 pass over pulley wheels or sheaves 56 carried by the supporting plate 46. The pulley wheels 56 are pivoted between pairs of hangers 57 rigidly secured to and depending from the plate 46. The cables 54 may be extended to any suitable point whereby when the cables are operated the hood can be raised and lowered, and if desired a suitable counter balance may be attached to the cables to allow the hood 49 to be moved to any suitable position and to remain in said position.

In use, the stove may be suspended within the brooder, coop or the like, by attaching the supporting plate 46 to the ceiling, frame, or support, by means of the hangers 47. Coal, charcoal, wood or other suitable fuel may be deposited within the annular fire box, by opening one or more of the doors 25, and may be lighted, whereby the products of combustion pass upwardly between the casing 1 and drum 11, and thence between the tops of said drum and casing, and finally up through the flue 5. Air is admitted through the openings 33 and nozzles 32 into the annular ash pit, and passes upwardly through the grate to support the combustion of the fuel, the amount of air admitted being controlled by the adjustment of the annular damper 37. It is to be noted that the air surrounding the casing is not only heated, but the air within the drum 11 is also heated, the heated air passing upwardly through the flues or outlets 15 from the drum 11. The hood 49 serves to catch the heated air, and prevents the same from rising upward, whereby the heated air is directed to all sides from the edge or rim of the hood.

The fire within the stove may be supported below one or more of the openings 24, according to the amount of heat desired, and the stove may be suspended sufficiently above the floor to allow the chickens to rove under the stove. The suspension of the stove above the floor also permits one or more partitions to be disposed below the stove for segregating the chickens, yet allowing

the various groups of chickens to stand below the stove. The stove will practically have a uniform heat throughout all sides thereof, and the hood 49 may be adjusted vertically to the desired height above the stove, according to the circumstances. The hood can be let down over the stove, whereby the heated air is confined within the hood, and is directed downwardly from the stove. The stove can be revolved about a vertical axis, which enables the attendant to properly take care of the stove without walking around the same, and the annular damper permits the inflow of air to be controlled effectively, it being noted that the damper can be operated from any side of the stove. The stove has air inlets completely around the same, whereby the air is properly supplied to the fire box.

The stove provides an admirable means for heating a brooder, chicken coop, or the like, although the stove may be put to various uses.

Having thus described the invention, what is claimed as new is:

1. A suspended swingable flue, and a rotatable stove suspended therefrom.
2. In a device of the character described, a supporting member having an opening, a flue, a member secured to said flue and having a concaved portion seated in said opening, and a stove suspended from said flue.
3. In a device of the character described, a supporting member, a flue suspended therefrom, a stove suspended from the flue, 100 a hood slideable upon the flue above the stove, pulleys carried by said supporting member, and flexible elements attached to said hood and passing over said pulleys.
4. In a device of the character described, 105 a suspended flue, and a rotatable stove suspended from the flue and having an annular fire box and covers therefor.
5. In a device of the character described, a suspended flue, and a stove casing suspended from and having its top rotatably connected to the lower end of said flue.
6. In a device of the character described, a suspended flue, a stove casing having its top connected to the lower end of said flue, 115 a drum within the casing having upper outlets communicating through the top of the casing, a common bottom for the casing and drum comprising hinged sections, and means for holding said sections in place against the lower end of the casing.
7. In a device of the character described, a suspended flue, a stove casing having its top connected to the lower end of said flue, 125 a drum within the casing having upper outlets communicating through the top of the casing, a common bottom for the casing and drum comprising hinged sections, and means for holding said sections in place against the lower end of the casing, the bottom sec- 130

- tions having arcuate upstanding flanges to overlap the lower ends of the casing and drum.
8. A stove comprising a cylindrical casing, a cylindrical drum therein, an annular grate between the casing and drum, and inwardly projecting air inlet nozzles attached to the casing to supply air under the grate.
9. A stove comprising a cylindrical casing having an annular series of air inlet openings, and an annular damper surrounding the casing and having inwardly offset portions movable across and away from said openings to control the inlet of air.
- 15 10. A stove comprising a cylindrical casing

having an annular series of air inlet openings, and having outstanding members between said openings, and an annular damper having slots receiving said members and having inwardly offset portions movable 20 across and away from said openings for controlling the inlet of air.

In testimony that I claim the foregoing as my own, I have hereto affixed my signature in the presence of two witnesses.

JOHN HENDERSON.
